BUILT-UP WOOD PANEL

Frederick Weyerhaeuser, St. Paul, Minn., assignor, by mesne assignments, to Rock Island Millwork Company, Rock Island, Ill., a corporation of Illinois

Application September 18, 1948, Serial No. 49,911

2 Claims. (Cl. 20—91)

1

This invention relates to improvements in wood panels.

In the manufacture of wood panels from boards, kerfing of the boards longitudinally or grain-wise has been proposed heretofore in an effort to avoid excessive, uncontrolled expansion, and warpage of the panel under circumstances producing unbalanced surface conditions. For some purposes, as where the boards are concealed in use, kerfing on one or both sides is not objectionable, except for the structural weakening of the boards that results from the kerfing, as a result of which weakening, conventional nailing of the boards to a supporting framework, as to studding or joints, retains the kerfed boards in position generally against the forces that tend to warp or cause them to change dimensionally. Merely kerfing a surface of a board does not in itself effect stabilization of the board, that is, kerfing alone does not prevent cross-grain expansion and contraction, nor prevent that warpage or cupping resulting from unbalanced moisture conditions within, or affecting unequally the faces of the board.

It is an object of the present invention to provide an improved panel made of one or more boards that is substantially stabilized and that may be provided with one or with both faces that are uninterrupted or continuous and thus subject to conventional decorating or finishing where desired for use in exposed positions.

Another object of the invention is to provide a panel structure that, while kerfed grain-wise, is sufficiently rigidified crosswise as to make possible the manufacture of panels of substantial width without danger of breakage during subsequent handlings.

In the accompanying drawings wherein panel structures illustrative of the invention are shown:

Fig. 1 is a perspective view of a panel formed of boards assembled to provide one continuous decorative surface or face.

Fig. 2 is an enlarged broken end elevation of the panel shown in Fig. 1.

Fig. 3 is a broken perspective view of a composite panel formed by securing together, back to back, two panels of the type shown in Fig. 1.

Fig. 4 is a broken perspective view of a modification of the panel shown in Fig. 3.

Fig. 5 is a broken side elevation of the panel shown in Fig. 4.

Fig. 6 is an end view of the panels shown in Figs. 3 and 4.

The panel structure shown in Fig. 1 is formed of boards 10 glued together edge-wise with butt

2

joints as indicated at 11. The glued edges may be matched if desired. The boards employed in forming the panel may be of equal or of random widths and may be of different lengths if desired. Where boards of length less than the length of the panel are utilized, the end joints 11a may be glued matched or butt end joints, the former being preferred. Hence, in accordance with the present disclosures, boards that would be considered in some wood-working plants as unsuitable for building up panels may well be utilized in the manufacture of panels embodying the present improvements.

The boards 10 are kerfed on one side, which side usually will constitute the rear face or back of a finished single panel. Hence, in the kerfing of the boards, consideration may well be given to surface conditions such as grain, knots, etc. of individual boards where the completed panel is to be employed in locations where the front face will be exposed and decorated to provide a wall or like surface. When the panels are to be employed for structural purposes only, as for sheathing, subfloors or the like, little or no attention need be given to the selection of board faces prior to kerfing operations.

The illustrative panel shown in Figs. 1 and 2 is provided with kerfs 12 that extend longitudinally, that is, lengthwise or substantially grain-wise of the individual boards, and are suitably spaced apart and are of appropriate depth relative to the thickness of the panel. If the panel shown in said figures is assumed to be approximately $\frac{1}{2}$ inch thick, the kerfs 12 may be $\frac{3}{8}$ inch in depth and in width about $\frac{3}{16}$ inch. A spacing of $\frac{3}{4}$ inch between kerfs has been found satisfactory in panels of the thickness mentioned.

The forward face 13 of the panel is unkerfed and is in fact the outer face of a continuous portion of the panel disposed outwardly of the plane determined by the bottoms of the kerfs 12. This continuous portion is designated 14 and is approximately $\frac{1}{8}$ inch in thickness in the panel of the specifications given above.

Extending transversely of the panel formed by the boards 10 is a plurality of grooves or channels 16 for receiving splines 17. The channels 16 are shown of the same depth as the kerfs and should not be of less depth although they may be somewhat deeper to provide continuous bottom surfaces on which the lower edges of surfaces of the splines can seat to insure close contact for the glue joints between the splines 17 and the bottoms of said spline-grooves 16. The splines shown in Figs. 1 and 2 may be $\frac{1}{4}$ inch wide and are shown of a thickness such that

their outer edges lie flush with the rear face 13a of the panel. The size of the splines however, may be varied as required, the dimensions of the same and of the panel, and the kerfs being that employed in a practical panel structure using commercially available wood, such as pine, for example. The splines are formed of any suitable material which is lengthwise stable, that is, not subject to appreciable lengthwise expansion or contraction. Where the splines are made of wood, the grain of the splines extends lengthwise and hence the splines do not vary in length with varying conditions of humidity, being formed of known woods having no appreciable expansion or contraction lengthwise by reason of variations in moisture content.

A panel structure such as is shown in Fig. 1 may be manufactured in substantial widths, for example, two or two and one half feet or more and of such length as is conventional commercially, for example, eight feet. However, the invention permits of any length and of any width. The number of splines employed is such as to rigidify the panel transversely not only to prevent breakage lengthwise during handling but to stabilize the panel against warpage or cupping and dimensional change crosswise of the wood by reason of variations in moisture content of the wood, or by the treatment, as by painting, of the continuous outer decoratable face 13.

As described above, the kerfing extends beyond the median plane of the panel, leaving only a relatively thin continuous board portion 14 lying between the forward face 13 of the panel and the parallel plane passing through the bottoms of the illustrated kerfs 12. This portion of the board is not stabilized by reason of the kerfs and expansion or contraction thereof tends to vary the total width of the panel. However, due to the fact that the portion 14 is relatively thin, the expansive and contractive forces exerted thereby due to changes in moisture content, or the tendency of said portion to warp from its original plane, are controllable by the splines 17 which are sufficient in number to stabilize the panel under normal conditions of storage and use. In the drawing, six splines are shown spaced longitudinally along the panel. However, a greater number of splines may be employed if desired, or splines of greater width or of material affording greater resistance to warpage or dimensional alterations may be employed. For ordinary commercial purposes however, the panel, as above described, is satisfactory since it is designed to be secured, as by nails, to a rigidifying frame or support, such as studding, rafters, joists or the like structural units that resist warpage even under extreme conditions that effect an unbalance of the forces affecting the faces of the panel, as painting, papering or other finishing applied to the face 13 thereof.

The kerfs 12 subdivide the board and form of the rear portion 18 of the panel longitudinally disposed ribs 19, of which ribs lateral or crosswise expansion is accommodated by the adjacent kerfs without affecting the over-all width of the panel. The strips 19 stiffen the panel against transverse flexure or warpage along a transverse axis, while the splines stabilize the forward portion 14 against crosswise dimensional alteration and stiffen the panel as a whole against longitudinal warpage or flexure along a longitudinal axis.

Where a more completely and permanently self-stabilized panel is required, two panels of the character shown in Fig. 1 may be secured

together, back to back, to provide a composite panel as shown in Figs. 3 to 6 inclusive.

In Fig. 3 the composite panel therein illustrated comprises two of the above described single panels glued together, the kerfed surfaces being in contact. The kerfs preferably are in staggered relation and the splines are shown spaced substantially uniformly from end to end of the panel. The two mating panels are designated for convenience of identification, by numerals 20 and 21, the former having kerfs 22 and splines 23, while the latter panel 21 has similar kerfs 24 and splines 25. It will be seen in Fig. 3 that the splines 23 and 25 of the two mating panels, 20 and 21, are not in registration, but rather alternate in a lengthwise direction of the panel. Such arrangement is not essential since the splines may be arranged in registration, if desired, or splines common to the two mating panels may be employed as shown at 26 in Figs. 4 and 5. In this respect only, the panel of Fig. 4 differs from the structure shown in Fig. 3 and hence a description of the latter will suffice as a description of the former except for the difference just mentioned.

The mating panels 20 and 21, are secured together as by gluing along their kerfed faces, which are the rear faces of the panels considered individually, and which faces constitute a glue line on plane 27 in the composite panel. Where splines 26, common to the two panels are employed, as shown in Fig. 4, the splines 26 may be glued in the registering channels of the two mating panels conveniently with the assembly of the two panels 20 and 21, or the splines may be glued in the channels of one of the panels first, and in the channels of the second panel at the time of assembly and the gluing together of the two panels, or, if desired, some of the common splines may be glued into some of the channels of one panel and the remaining splines in the other channels of the second panel prior to assembly of the two panels. A suitable press is employed in the assembly operation.

After a composite panel has been removed from the press, the composite structure will be found to have remarkable stability, capable of resisting effectively the forces that normally cause warpage and dimensional variations transversely of wood panels of similar size. Such composite panels may therefore be used not only as units of structures which are parts of buildings, as in sheathing, sub-flooring or the like, which units by reason of their size reduce the time and labor involved in the erection of such structures. They may also be employed as exposed elements in wall structures and be finished, that is stained, varnished, enamelled, painted or papered on one surface or on both surfaces where desired. The stability of the composite panels provided by the construction disclosed is such that their range of usefulness is not limited to locations affording a rigid backing or support in resisting warpage or transverse dimensional change.

As shown in Figs. 3 to 6 the composite panel has two relatively thin continuous portions, 28 and 29, constituting the outer faces of the panel, and each corresponding to the portion 14 of Fig. 1. The facial portions 28, 29, are integral, in the form shown in Fig. 3 with the respective longitudinal ribs 30 and 31, into which ribs the remainder of each mating panel is, in effect, divided by the parallel kerfing. The relatively thick portions of the panel, represented by the ribs 30 and 31, do not produce transverse expansion or

contraction of the panel as a whole since the spaces provided by the adjacent kerfs effectively accommodate the expansion of the individual ribs. Hence the splines actually are required only to resist the expansive and contractive forces exerted by the thin continuous facial portions 28, 29, and the number and size of the splines employed is at least adequate for that purpose.

The expansion of the ribs 30 or 31, which are the relatively thick portions between kerfs of each single panel tends to cup or deform the exterior surface portions 28 and 29. However, the rear faces of the ribs of each single panel are glued to similar faces of the mating panel, whereby the tendency of any rib to expand or contract transversely is resisted, and in fact neutralized, by the attached rib or ribs, especially where the kerfs are staggered as shown in Figs. 3, 4 and 6. For example, tendency of any one of the ribs 10 to expand or contract, as the strip designated A, Fig. 6, is accommodated by the adjacent kerfs 22, but since rib A is glued to the opposing half portions of ribs B and C of the mating panel (which ribs B and C will normally have a like tendency to expand or contract under any condition tending to cause transverse dimensional variation of rib A) movement of the left hand portion of rib A to the left due to expansion or contraction will be opposed by a similar tendency of the right hand portion of rib B to move to the right. Likewise movement to the right of the right hand portion of rib A will be opposed by the tendency of the left hand portion of rib C to move to the left. Hence the staggered relation of the kerfs, providing the described overlapping relation of the ribs, provides neutralizing resistances to lateral expansion or contraction of the internal portion of the composite structure that would otherwise tend to distort the panel or alter its crosswise dimension or tend to produce cupping in the outer faces 28, 29. The staggered relation of the kerfs rather than a registering relation as between kerfs of the mating panels, is preferred also for the reason that a structurally stronger composite panel is thereby provided. As will be apparent in Fig. 6 the original opening of each kerf in one mating panel is backed by a solid thick rib of the other mating panel. Thus, the weakening of the original board by the kerfing operation, is overcome by a compensating reinforcement effected by securing a relatively thick rib 30 or 31 as a closure for each kerf. Likelihood of longitudinal splitting of the plane panel face along a kerf therefore is materially reduced by the described staggered relation of the kerfs. Hence, assemblage of the mating panels with the kerfs in registration is not preferred.

While the mating panels are shown and described as being formed of boards of such thicknesses that kerfing thereof to provide the integral thin facial layers 28 and 29, and strips 30 and 31, is practicable by known woodworking equipment, it is within the contemplation of the invention that the ribs need not be integral with the facial layers in the limited sense described, but that the ribs may be separate strips integrated with thin layers by being glued to the latter in

spaced parallel relation to provide spaces corresponding to the described kerfs, and that such glued-up panel, after being provided with splines as above described, may be employed similarly to the structure shown in Fig. 1, or may be assembled in pairs to provide composite panels of the general character described.

Other modifications of the illustrative structure utilizing the principle of the present disclosure may be employed without departing from the spirit of the invention defined by the following claims.

I claim:

1. A two-layer structure comprising two panels adhesively united facewise to each other, each panel comprising a plurality of boards of uniform thickness placed edge to edge in panel formation with the grain of all the boards extending parallel to the resulting edge-joints of the panel, the resulting assembly having one face uninterrupted and the other face provided with a multiplicity of kerfs all having uniform depths which are a major portion of the thickness of the assembly, the kerfed face having spaced parallel rectangular cross-sectional channels cut therein to the same depth as the kerfs and extending at right angles to the kerfs, and lengthwise-stable splines filling said channels and adhesively secured to the bottoms thereof, the said two panels in being adhesively united at their kerfed faces having each kerf opposed by unkerfed wood in the opposite panel.

2. A two-layer structure comprising two panels adhesively united facewise to each other, each panel comprising a plurality of boards of uniform thickness placed edge to edge in panel formation with the grain of all the boards extending parallel to the resulting edge-joints of the panel, the resulting assembly having one face uninterrupted and the other face provided with a multiplicity of kerfs all having uniform depths which are a major portion of the thickness of the assembly, the kerfed face having spaced parallel rectangular cross-sectional channels cut therein to the same depth as the kerfs and extending at right angles to the kerfs, the said two panels in being adhesively united at their kerfed faces having each kerf opposed by unkerfed wood in the opposite panel, and also having their channels in register, and a common lengthwise-stable spline in each pair of registering channels adhesively secured to the bottoms of the registering channels.

FREDERICK WEYERHAEUSER.
